UNITED STATES PATENT OFFICE

CECIL GEORGE QUICK, OF ELMHALL, AND WALTER WILLIAM FORBES DENNE, OF NEW MELDEN, ENGLAND, ASSIGNEES TO R. HOE & CO., INC., OF NEW YORK, N. Y., A CORPORATION OF NEW YORK.

LATE NEWS PRINTING MECHANISM

Application filed January 6, 1930, Serial No. 418,897, and in Great Britain July 3, 1930.

This invention relates to improvements in late news devices for newspaper printing machines, by which supplementary matter such as late news and edition headings are printed.

Heretofore, the late news printing boxes or form holders and their associated inking mechanism have been supported by brackets secured to bars extending from side to side 10 of the machine and located at one side of the late news printing mechanism, the arrangement thus being such that the resultant force due to the weight of the boxes and the inking mechanism has been offset horizontally with respect to the cross bar. A twisting motion was thus imposed on the cross bar which, in consequence, has had to be extremely massive. Moreover, the vibration due to the blow that results from the successive groups of type moving into and out of contact with the impression cylinder, has been transmitted through the brackets to the inking mechanism, with the result that uneven inking occurred.

According to the present invention, the late news and edition heading boxes are supported on a shaft or the like, mounted in the main frame of the machine independently of the support for the inking mechanism, which latter support is arranged substantially in the line of force due to the weight of the mechanism.

With such an arrangement, the vibration imparted to the shaft for the boxes is transmitted direct to the main frame of the machine, the inking mechanism is substantially unaffected thereby, and the support for the inking mechanism is subjected substantially only to bending stresses.

A support for the inking mechanism preferably comprises a main cross bar or stretcher, to which are secured frames carrying the ink fountain and distributing rollers, and a cross bar which passes through the frames and on which the ink distributing drums rotate.

The main object of the present invention is to provide an arrangement in which the late news mechanism is rigidly supported in such position as to be accessible, and so as

not to interfere with the reactions of other elements of the machine.

It is also an object of the invention to provide a late news mechanism of generally improved construction, whereby the device will be durable and simple in construction, as well as convenient, practical, serviceable and efficient in its use.

With the foregoing and other objects in view, which will appear as the description 60 proceeds, the invention resides in the combination and arrangement of parts, and in the details of construction hereinafter described and claimed, it being understood that various changes in the precise embodiment 65 of the invention herein disclosed may be made within the scope of what is claimed, without departing from the spirit of the invention.

The preferred embodiment of the invention is illustrated in the accompanying drawings, wherein:

Figure 1 is a transverse section partly broken away, of a printing machine that comprises four late news printing devices, 75 and two devices for printing edition headings.

Figure 2 is a sectional view of the mechanism as seen on the line II—II of Figure 1 and in the direction of the arrow.

Referring to the drawings, the numerals 1 and 2 indicate main side frames of a printing machine, in which is journaled an impression cylinder 3. A shaft is indicated at 4 on which form holders or boxes 5, 6 and 7, adapted to hold supplementary printing forms are adjustably mounted, and it will be understood that the section broken away may contain both late news type and edition headings, and the box 6, late news type only. The shaft 4 is journaled in the main frames 1 and 2, and is supported intermediate of its ends by a hanger bearing 9, having flanges 10 and 11 adjustably bolted to cross frame members 12 and 13, which are secured 90 at their ends to the side frames 1 and 2.

The mechanism for inking the type contained in the boxes, is supported by sub-frames 14, 15; 16, 17; and 18, 19 respectively. Each of the subframes is bolted to the cross 100

bar 22 by bolts 23 whose heads extend into slots 23', formed in the cross bar 22, whereby the frames can be adjusted to any desired position. The cross bar 22 is secured by bolts 23" to the side frames 1 and 2.

A cross rod 24, is secured at its ends to the side frames 1 and 2, and passes through the several subframes bearing the numerals 14 to 19 inclusive.

• The inking mechanisms are all of a well-known kind and each comprises an ink fountain 25, having a fountain roller 26, a doctor roller 27 mounted on arms 28 that are located in any well-known manner, a distribution drum 29, rollers 30 and 31 which are reciprocated across the periphery of the drum 29, and form rollers 32 and 33.

• In the drawings, the inking mechanism described is illustrated for the subframes 14 and 15, and in part for the subframes 16 and 17. It will be understood that the mechanism is duplicated on the other side of the machine.

The ink fountains 25 are bolted to the subframes 14 and 15 and to other similar subframes. The pivots of the arms 28 are mounted on the said frames and the rollers bearing the numerals 30-33 inclusive are mounted in brackets 35, 36, 37 and 38, secured to the frames, while the ink distributing drums 29 are arranged to rotate freely on the rod 24. The rotation of the distribution drums 29 and the fountain rollers 26 is effected by gearing, indicated generally at 39, and driven by gear wheels 40, secured to the shaft 4, which latter may be driven in any suitable manner, the gearing 39, being supported by the sub-frames 15 and 17. Guards 41 and 42 that are formed in two sections, are pivoted at 43 and clamped in position by bolts having thumb nuts as indicated at 44.

It can be seen that any vibration set up in the shaft 4 is transmitted direct to the side frames 1 and 2, and hence is not transmitted to the inking mechanism, thus insuring even inking. The weight of the mechanism is supported by the cross bar 22 as a substantially pure bending load, permitting the bar to be made of relatively light construction since it is not called upon to resist a twisting stress, and positioning of the bar 22 below the inking mechanism instead of at one side, as has heretofore been the practice, reduces the transverse space occupied and thus permits greater space between the various units of the machine, thereby insuring greater accessibility.

What we claim is:

1. In a late news device for a rotary web printing machine, a pair of side frames, form holders adjustable on a shaft having bearings supported by the frames, a cross bar in substantially vertical alignment with the shaft, and a plurality of pairs of subframes adjustably attached to the cross bar and

adapted to support inking mechanisms in operative relation to the form holders.

2. In a late news device for a rotary web printing machine, a pair of side frames, a form holder on a shaft having bearings supported by the frames, a cross bar, subframes attached to the cross bar, a cross rod engaging the subframes and secured to the side frames, and an inking mechanism supported in the subframes having an ink drum rotatable on the cross rod.

3. In a late news device for a rotary web printing machine, a pair of side frames, a cross frame member secured to the side frames, a form holder on a shaft having bearings supported by the frames and the cross frame member, a cross bar, and subframes attached to the cross bar adapted to support an inking mechanism in operative relation to the form holder.

4. In a late news device for a rotary printing machine, a pair of side frames, a form holder on a shaft rotatably supported in bearings carried by the side frames, a cross bar, subframes attached to the cross bar, an inking mechanism supported in the subframes having an ink drum rotatable on the cross rod, a gear connected to the form holder, and gearing for driving the inking mechanism from said gear.

5. In a late news device for a rotary printing machine, a pair of side frames, a plurality of form holders on a shaft rotatably supported in bearings carried by the side frames, a cross bar, a plurality of pairs of subframes attached to the cross bar, a plurality of inking mechanisms supported in the subframes, a gear on the shaft adjacent each form holder and separate gearing for driving each inking mechanism from the said gears.

In testimony whereof, we affix our signatures.

CECIL GEORGE QUICK.
WALTER WILLIAM FORBES DENNE.
